UNITED STATES PATENT OFFICE.

ALEBERT SHEATHER, OF ELIZABETH, NEW JERSEY.

OIL BURNER.

Application filed October 18, 1921. Serial No. 508,461.

This invention relates to an improved oil burner adapted for use in furnaces and the like, which atomizes oil thoroughly so that it is broken up into very small particles 5 with a minimum amount of steam or air used as an atomizing agent.

The invention is designed to provide a burner of this kind in which the flame is so spread that there is no localizing on the 10 surface to be heated. In other words, the flame is distributed so that no part will be subjected to excessive heat, which local excessive heating, when it occurs, is damaging to such elements as the tubes of water tube 15 boilers.

The burner provides a flame which is of a general fan-tail effect which allows a perfect mixture with the air in all parts of the furnace, thereby providing a resemblance to 20 a furnace fire made from coal.

This invention is designed to provide a burner having a head which is preferably made in one piece, being cast with a core so as to provide a device with substantially 25 thick walls, the head having a rounded front face and having in this front face slots which are usually milled through to communicate with a chamber inside the head so as to form 30 arcuate lips between the slots, these arcuate lips on the rounded front face providing a fan-shaped flame. More than one slot is usually required, but it will be evident that if it is found in particular cases that only 35 one slot is required, then only one slot would be provided.

The invention is illustrated in the accompanying drawing, in which Figure 1 is a side view of a burner of the improved type, partly broken away to show the interior 40 thereof. Figure 2 is a front view of the nozzle of the burner. Figure 3 is a section on line 3—3 in Figure 1, and Figure 4 is a section on line 4—4 in Figure 2.

The burner may be of any desired size 45 and is preferably made with the passage 10 therethrough, the casing being enlarged on the rear end, as at 12, to form a mixing chamber 13. The mixing chamber 13 has one inlet opening which receives a pipe 14 50 which supplies an atomizing agent, such as air or steam under pressure, this pipe having its inlet usually in line with the passage 10, and a pipe 15 is connected to the nozzle, the pipe 15 being adapted to convey, from 55 a suitable source of supply, the fuel oil.

The pipe 15 extends within the chamber

12 to approximately the axial center thereof so that the outlet end 16 of the oil supply pipe is in the center of the stream of the atomizing agent and the oil is thus atomized 60 at the center of the flow of steam, and in this atomized form is then carried through the straight passage 10 to the head 17 which is provided with the chamber 18. The front end of the head 17 is provided with slots 65 through which the atomized fuel oil is passed, these slots, such as at 19, being approximately parallel with the axis of the nozzle, and for clearness of description these will be termed as horizontal. The front face 70 of the head 17 being rounded and these slots being cut straight across at their inner ends, they provide arc-shaped lips between which the atomized fuel emerges.

I prefer to also provide a lower slot 20 75 which is inclined, as will be seen from Figures 1 and 2, so that it points upward and forces a stream of atomized fuel into the stream or streams emerging from the slot or slots 19, which further divides the small 80 particles of oil; in other words, still further atomizes the oil in the emerging stream and forms a fan-tail flame. This divergent or obliquely inclined stream emerging from the slit 20 gives a slight arch to the flame and prevents any tendency toward excessive 85 downward movement of the flame, thus acting to prevent burning out of grates and the like when it is used over them.

I prefer to make the chamber 18 of the 90 same size throughout, and the slots 19 and 20 extending across the face or front end of the nozzle insure a minimum amount of fuel passing out through the extreme ends 95 21 of these slots, thus avoiding any impinging of fuel on the side walls of the furnace.

The burner is easily handled, it being, of course, understood that the pipes 14 and 15 are provided with suitable valves for the regulation of the amount of material supplied through these pipes, and it will be further seen that by turning on the atomizing agent, steam or air, first, and then slowly feeding fuel oil through the pipe 15 until ignition takes place, any waste of fuel is 105 eliminated and there is no possibility of explosions taking place in starting.

It will be evident that minor changes can be made in the form of the parts without departing from the scope of the invention. 110

I claim:

A burner comprising a one-piece casing

enlarged at one end to form a mixing chamber with an end inlet and a side inlet and enlarged at the other end to form a head with a curved front and slits in the front, the upper slit being parallel with the axis of the casing and the lower slit being inclined to form an arcuate slit so that the

stream emerging therefrom mixes with and arches the flame of the burner.

In testimony that I claim the foregoing, ¹⁰ I have hereto set my hand, this 17th day of October, 1921.

ALBERT SHEATHER.
